C. R. SWANSON.
FLOATING EQUIPMENT.
APPLICATION FILED OCT. 9, 1917.

1,268,179

Patented June 4, 1918.

UNITED STATES PATENT OFFICE.

CARL R. SWANSON, OF MARSHALL, MINNESOTA.

FLOATING EQUIPMENT.

1,268,179.

Specification of Letters Patent.

Patented June 4, 1918.

Application filed October 9, 1917. Serial No. 195,545.

To all whom it may concern:

Be it known that I, CARL R. SWANSON, an American citizen of the United States, residing at Marshall, in the county of Lyon

5 and State of Minnesota, have invented certain new and useful Improvements in Floating Equipment; and I do hereby declare the following to be a full, clear, and exact description of the invention, such as will enable others skilled in the art to which it

10 appertains to make and use the same.

This invention relates to floating equipment for soldiers or others and has for its object to provide improved means whereby 15 a soldier may pass through rivers, lakes, or other bodies of water without sinking.

A further object of the invention is to provide means whereby the soldier will be relieved of the greater part of the weight 20 of his gun, while passing through a body of water.

With these objects in view, the invention consists in the improved construction, arrangement, and combination of parts hereinafter fully described and afterward specifically claimed.

In order that the construction and operation thereof may be readily comprehended, I have illustrated an approved embodiment 30 of my invention in the accompanying drawings and will now proceed to fully describe the same in connection with said drawings, in which—

Figure 1 represents, in front view, a soldier fully equipped with the several parts 35 of my invention,

Fig. 2, a longitudinal sectional view of one of the air bags,

Fig. 3, an enlarged transverse sectional view of the broken off inflating end of one of the wind bags,

Fig. 4, a transverse sectional view of the inflating end of one of the wind bags,

Fig. 5, a view in elevation, of one of the 45 wind bags for attachment to a gun, and

Fig. 6, a rear view of the body, showing a bag to be fitted on the back.

Like reference characters mark the same parts, wherever they appear in any of the 50 figures of the drawings.

Referring specifically to the drawings, 6 indicates a hat or helmet on the soldier, of a suitable material such as linoleum, which will not be ruined, or seriously damaged, by 55 contact with water and 7 indicates a breast plate of like material, the breast plate be-

ing secured to the body by any suitable means, including straps 8 passing over the shoulders of the wearer.

At 9, 9, are inflating air or wind bags 60 secured to the edges of the breast plate by suitable means, as at 10, 10, while at 11, 11, are similar inflatable bags secured to the sides of the leggings, puttees, or clothing, of the soldier at 12, 12, by any suitable 65 means, the leggings or puttees being also of like material proof against injury by water.

At 13 is shown a similar inflatable bag adapted to be secured to a gun and a bag may be worn on the back as in Fig. 6. 70

The inflatable bags 9, 11 and 13 are of rubber or other suitable material and within them are smaller bags, or balls, as at 14, in this instance five in number in each of the larger bags, such balls being of thinner rub- 75

From each of the small bags or balls extends a tube 15 to and substantially through the neck 16 of the larger bags, each tube terminating in a ball valve, as at 17, arranged around a central valve 18 provided for the inflation of the larger bags, these valves being carried by a metal cap 19 adapted to be threaded upon the terminal of any suitable supply of air under pres- 80

ure, and all of the valves being self closing 85 against the escape of air from the bags or balls.

All of these bags and balls being of slight construction, they will not very materially 90 inconvenience the wearer when collapsed and when desired or needed, owing to the necessity of the wearer passing through a body of water, they may be inflated from any source of air under pressure, the larger 95 bags being pumped, if desired, as hard as a pneumatic tire, and the smaller bags or balls, which may be made of the same class of rubber as the inner tube of a tire, being correspondingly inflated. 100

Wearing the inflated bags, as shown in Fig. 1 of the drawing, a soldier may freely pass through bodies of water of any depth, the buoyancy of the bags being sufficient to prevent the sinking of the wearer, and the 105 bag attached to his gun will prevent its sinking and will relieve the soldier of its weight while passing through deep water.

Should a bullet pass through one of the larger bags, it would be very unlikely to injure more than one of the inflated balls, therefore leaving the other balls inflated to 110

buoy up the punctured outer larger bag and the punctured ball.

The advantages attending the use of my invention will be obvious from the foregoing description and it will be observed that I have not limited the construction of the parts as to shape or material as many forms and materials might be utilized, and any source of air under pressure may be used, such as a compressed air tank, when available, or ordinary pumps such as used for inflating tires.

Many changes and variations may also be made in the attaching means for the bags, without departing from the spirit of the invention.

Having thus fully described my invention, what I claim and desire to secure by Letters Patent of the United States, is:

- 20 1. An equipment for soldiers comprising a suitable breast plate, of material proof against injury by water, secured to the breast, and inflatable bags secured to the sides of the breast plate.
- 25 2. An equipment for soldiers comprising leggings or puttees of material proof against injury by water and inflatable bags secured to the sides of such leggings or puttees.
- 30 3. An equipment for soldiers comprising a suitable breast plate, of material proof against injury by water, secured to the breast, and inflatable bags secured to the sides of the breast plate, and leggings or puttees of material proof against injury by
- 35 water and inflatable bags secured to the sides of such leggings or puttees.

4. An inflatable bag adapted for attachment to parts of a soldier's outfit, provided with a plurality of inner smaller bags or balls, and means for simultaneously inflating all of said bags or balls. 40

5. An inflatable bag adapted for attachment to parts of a soldier's outfit, provided with a plurality of inner smaller bags or balls separately inflatable, the outer and 45 each inner bag being provided with suitable inflating means comprising valves which automatically close against outward passage of air.

6. An outer inflatable bag provided with 50 a neck, a central inflating valve in said neck through which to inflate the bag, a plurality of inflatable balls inside the bag, tubes leading from the balls into the neck of the outer bag, and a valve for each ball 55 tube in said neck, said valves surrounding the central valve of the outer bag.

7. An inflatable bag provided with a neck, a cap closing said neck, a valve in said cap for inflating said bag, a plurality of bags 60 or balls positioned within said first bag, corresponding valves in said cap, and tubes connecting said last named valves with said last named bags or balls.

In testimony whereof I have signed my 65 name to this specification in the presence of two subscribing witnesses.

CARL R. SWANSON.
